(57) **CLAIM**

The ornamental design for a color sample indication tool, as shown and described.

DESCRIPTION

FIG. 1 is a front view of the color sample indication tool of the present invention.

FIG. 2 is a rear view thereof.

FIG. 3 is a top view thereof.

FIG. 4 is a left side view thereof.

FIG. 5 is a cross-sectional view, taken along lines A-A of FIG. 1; and,

FIG. 6 is a cross-sectional view, taken along lines B-B of FIG. 1.

1 Claim, 6 Drawing SheetsFIG. 1

FIG. 2

FIG. 3

FIG. 4

FIG. 5

FIG. 6
